ABSTRACT OF THE DISCLOSURE

A time-delay control unit which can be provided in quantity for mine inactivation or demolition control. Each unit includes a casing in two complementary parts or halves held together by rivets and provided with a ventilated cylindrical chamber for a timer element or plug of elastomer material which is expanded or enlarged to fill the chamber by immersion in a volatile solvent prior to use. A spring-pressed movable piston or plunger bears against one end of the timer plug and is movable, as the volatile solvent evaporates and shrinks the plug, to withdraw a trigger pin from a firing pin or the like to actuate a detonator and thus fire and destroy adjacent mines or other explosive material surrounding the unit. The movable firing elements, which include the detonator and the firing pin, lie in an elongated transverse cylindrical channel at a right angle to and intersecting a similar and larger longitudinal cylindrical channel for the release and timing elements which include the elastomer timer plug, the plunger and the trigger pin.

The invention described herein may be manufactured, used and licensed by or for the Government for governmental purposes without the payment to us of any royalty thereon.

The present invention relates to time-delay or timing control means for initiating a function which is particularly adapted to the field of demolitions. More particularly the present invention relates to time-delay control means adapted for rendering explosive mine and demolition devices inactive after a predetermined period of time following a period of effective or tactical use.

It has been found that, under many tactical situations and in many commercial situations emplaced explosive mine and demolition devices require that they be rendered inactive or destroyed after some time delay following the desired period of effectiveness or use. There are many problems involved, if self destruction is considered as a mode. These problems include safety, reliability, cost, method of activation, time to functioning, long-term storage capability and ruggedness to withstand the average commercial and military environments. These problems have been inherent in ordnance devices for a long time and have never been completely solved.

In the past, in arriving at any solution to these problems a matching or balancing of one desired parameter against another has been involved. The cost of most devices heretofore produced has also been comparatively high, their activation procedure frequently hazardous, and the time of operation considerably variable. These devices have included mechanical escapements, electrical rundown timers, the dissolving of plastic barriers, and the transfer of measured amounts of liquid or gas through orifices. Up to the present, devices of this type have not been satisfactory mainly because of cost, safety, and arming procedures.

As a requirement for a known low-cost type of mine and as a result of extensive research into low-cost timing devices compatible therewith, a self destruct or inac-

2

tivation unit has been provided. These mines are made to arm by the evaporation of a volatile solvent which has been found to be effective in principle for timing purposes.

It is therefore an object of this invention to provide an improved time-delay control unit of low-cost construction which may be particularly adapted for mine destruction and inactivation, in which the principle of the evaporation of a volatile solvent is put to effective use with material in suitable form to hold up under long term storage and maintain proper characteristics to assure a high degree of reliability, and in which a simple and effective release mechanism is provided to assure adequate functioning of the unit.

It is also an object of this invention to provide an improved and effective time-delay detonator unit of the type referred to of a relatively small size and low cost adapted to be dispersed in quantity over an area such as a mine field and to be self destructive after a predetermined and adjustable period of time.

In accordance with the invention, materials were sought and found which responded to the evaporation process and these were arranged to be used in a low-cost simple structure of plastic material with metallic inserts. After investigation of various materials it was found that enlargement or expansion of an elastomer material in a volatile liquid or solvent could be provided with the necessary mechanism to operate in a safe and stable time-delay control unit. The general concept arrived at was to retain a spring-loaded axially movable firing pin element in a cocked position by means of an expanded elastomer element as a result of absorbing the volatile solvent to substantially saturation. Upon exposure to the air, the elastomer element gradually loses the solvent by evaporation and reduces in size or contracts back to normal, permitting the firing pin to be released to strike a fixed firing element, such as a detonator or an electrical contact, to initiate a function such as an explosion process which fires a mine or other explosive element with which the device may be associated.

Important features of the present invention are inherent in the selection and use of an elastomer material, and such materials are found to be silicon rubber compounds or the buna type or styrene type. These materials must be selected to be compatible with the solvents used such as alcohols of the low molecular type. Among these are methanol, ethanol, propanol or chlorinated hydrocarbons such as the chloroforms, carbon tetrachloride, ethylene chloride and Dupont Freons.

In a preferred form of the invention, a main housing or casing is provided by two flat plastic cover plates which are held together by metallic rivets and enclose two cylindrical channels extending at a right angle to each other and intersecting. One channel, which may be termed the main or longitudinal channel, encloses the release and timing elements of the unit, while the other channel, which may be termed the transverse channel, encloses the firing elements of the unit. In general the firing elements include a spring-pressed firing pin movable axially along the transverse channel and a detonator positioned to receive the blow of the firing pin when released.

The firing pin is released by a release or trigger pin which extends through it and is carried on the end or attached to a spring-pressed movable piston or plunger in the longitudinal channel. The plunger bears against one end of an elongated timer element comprising a body or plug of elastomer material which fills a cylinder or chamber, also comprising part of the longitudinal channel for the timing elements, and through which a guide rod for the piston or plunger extends.

The elastomer timer element is expanded to fill the chamber and holds the piston or plunger in a position to retain the firing pin retracted. The chamber or cylinder is ventilated so that the volatile solvent may be evaporated slowly and thus causing the timer element body or plug to shrink or contract, which permits the plunger or piston to follow and move to withdraw the release or trigger pin from the firing pin. This occurs after a certain period of time and thus actuates the detonator and fires the unit and the mine or mines or other explosive devices around it for destruction or inactivation after a time delay.

The invention will further be understood from the following description when considered with reference to the accompanying drawings, and its scope is pointed out in the appended claims.

In the drawings,

FIG. 1 is a top or plan view of a time-delay detonating unit embodying the invention,

FIG. 2 is a view in elevation, and partly in section of the unit of FIG. 1, taken on the section lines 2-2 to show further details thereof in accordance with the invention,

FIG. 3 is a view in elevation, and partly in section of a form of the invention which is a modification of the unit shown in FIGS. 1 and 2, and

FIG. 4 is a fragmentary view, in elevation, of a portion of the unit of FIG. 3 showing a detailed modification thereof in accordance with the invention.

Referring to the drawings, wherein like elements, throughout the various figures are indicated by like reference characters, and referring particularly to FIGS. 1 and 2, right and left cover plates 5 and 6, respectively, of suitable plastic or like material are joined together to form a main housing or casing 7. The cover plates are held together by a number of rivets or like fasteners 8 and are complementary in character to provide the overall housing or casing for the unit as above referred to.

The two plates are relatively flat as shown more clearly in FIG. 1, and are enlarged at the rear end, or the left end as viewed in the drawing, to form a cylindrical screw housing 9 which is internally threaded to receive a manual timing adjustment screw 10. This may be unscrewed from the position shown in FIG. 2 and set to any desired position of withdrawal. It is held in place by a spring-pressed detent rod 12 which is substantially L-shaped and on an inner end, is engaged by a detent spring 13 to hold the rod 12 in any one of a series of angularly spaced longitudinally extending peripheral grooves or notches, one of which is shown at 14. An end cap 15 is provided as a cover for the rear end of the screw 10 and covers the notch in which the spring 13 is located, as shown more clearly in FIG. 2.

The timing adjustment screw 10 is one of a series of release and timing elements which extend end-to-end as a group forward through the housing 7 longitudinally. These include an elastomer timer element 18 in the form of an elongated round body or plug which fills a ventilated cylinder or chamber 19 which is in axial prolongation of the threaded opening for the screw 10. The timer element or plug 18 bears at its rear end against a backing washer 20 which, in turn, seats against the forward end of the adjustment screw 10 and is rigidly held thereby against rearward movement in any position of adjustment. The cylinder 19 is ventilated through ventilating openings 21 which are indicated more clearly in FIG. 1.

In the cylinder or chamber 19 and pressing against the forward end of the timer element or plug 18 is a spring-pressed or spring biased movable piston or plunger 22 which act as a movable timer-plug follower. This may be of steel or other suitable metal and has a central guide rod 23 extending therefrom axially through the body or plug 18 and into a central guide bearing opening 24 in the end of the adjustment screw 10. This bearing opening is of sufficient depth to permit the rod 23 to move freely as the piston or plunger 22 moves against and

follows the end of the body or plug 18 when it contracts in use for timing as will be explained.

On the forward side or face of the piston or plunger 22, and extending axially forward therefrom, is a release or trigger pin 26 which is reduced in diameter to pass through a hole or locking opening in a movable firing pin or firing element 27. The release spring or driving spring for the plunger or piston 22 is indicated at 28, and is of the compression type adapted to drive the piston or plunger 22 rearwardly or to the left as viewed in the drawing.

From the foregoing description it will be seen that the release and timing elements, above described, are arranged in end-to-end relation coaxially in a longitudinally extending channel through the casing which may be indicated generally at 29. Intersecting this channel at a right angle thereto and extending transversely across the casing between the cover plates is a second channel 33 which is adapted generally to fit the firing element or firing pin 27 and to hold it in position to guide it. In rear of the firing element or firing pin 27 is a driving spring 34 which seats on a spring base or plug 35 inserted into the channel and pinned thereto as indicated at 36. The channel 33 extends through the casing from one side to the other as indicated and at the opposite end contains a primer or detonator 37 which is mounted in a holder 38 also inserted into the channel and pinned thereto as indicated at 39. About the detonator 37 the channel 33 is constricted to provide a seat so that the detonator cannot enter the channel beyond the position shown in the figure and is held in a position to be struck by the moving firing pin or firing element 27 upon release by the trigger pin 26.

The unit is assembled initially with the timer plug 18 in a contracted condition, and with the release pin 26, the plunger 22 and the release spring 28 in place. Also the release pin 26 is inserted into the firing pin 27 which is withdrawn, against the force of the driving spring 34, to the retracted position shown in FIG. 2.

The timing adjustment screw 10 is set back to the desired withdrawn position to permit the full expansion of the timer plug 18 to take place as may be desired for any length of operational time, that is, to enlarge the chamber 19 to the desired size or length for the expansion and initial positioning of the plug 18. The unit is then immersed for a number of hours, such as 20 to 24 for example, in a volatile solvent which is readily adapted to be absorbed by and evaporated from the timer plug 18. This plug may be an elastomer such as

a silicon rubber compound or the buna or styrene type. The solvent used may be an alcohol of the low molecular type such as methanol, ethanol, propanol or a chlorinated hydrocarbon such as a chloroform, carbon tetrachloride, ethylene chloride or Dupont Freon.

During the time that the complete unit is immersed in the solvent, the latter flows through the ventilating openings into the body of the timer plug and causes it to expand to fill the chamber 19 and press against the piston or plunger 22 and against the backing disc 20 to the full length and extent of the chamber as provided by the adjustment of the screw 10. The more solvent it absorbs the longer the time for its evaporation and contraction of the timer plug 18 to the point where it is effective to release the firing pin, as will be explained hereinafter. Later, when briefly removed from the solvent, the detonator plug 37 is dropped into the channel 33 to its stop position and the detonator stop plug 38 is inserted and pinned. The unit is then reimmersed in the solvent and remains in storage therein until it is time for immediate use in the field. If use is to be not too long delayed and readiness must be maintained, the safety pin 31 may be removed before the unit is returned to the solvent solution.

For activation of this unit and placing it in use for timed functioning or detonation, it is merely necessary

to remove it from immersion in the solvent and expose it to the air at the desired location. Thus to initiate the timing cycle for military use it may be attached to or incorporated within an operative mine and will, in due course after a required time, fire and destroy the mine and thus set off a chain reaction of destruction if others are close enough for that operation. At any time before firing the unit may be returned to the solvent and immersed therein to interrupt the operation and restore the timing cycle.

The operation of the devices of FIGS. 1 and 2 is such that, as the volatile liquid evaporates from the timer plug 18, the material begins to contract and the longitudinal contraction permits the plunger or piston 22 to follow and compress it between the piston and the backing washer 20 until, by force of the release or driving spring 28, the trigger or release pin 26 is completely withdrawn from the firing pin or firing element 27 which is then driven forward under the power of the firing pin spring 34 to carry out a function such as to strike the detonator and initiate the explosion of any explosive material or mine in its immediate vicinity.

It has been found that the present unit is reliable in operation and dependable and efficient as a time-delay control unit. This is due in part to selection and use of the elastomer materials referred to, in suitable form as described, which hold up under long term storage and maintain proper characteristics to assure this reliability. Furthermore the simple and effective quick release mechanism provided in the structure as described which is of low cost, easy to manufacture and assemble and also provides for the further reliability and adequate functioning of the unit.

If the time is important, the adjustable time control device provided by the timer screw 10 is desirable, and also it is desirable that the chamber 19 and the body 18 of elastomer material be relatively long or elongated since it has been evaluated and found to reduce the effects of tolerance variations on the time to function. The two parts of the casing 7, that is, the left and right cover plates 6 and 5, are preferably of the ejection molded type. These parts may be made of such plastic materials as high density polyethylene, polystyrene and the like, with metal springs, firing pin, plunger, release pin and rivets used to drop into place in the molded areas provided therefor as shown in FIGS. 1 and 2. The device may be constructed and used as an expendable item since it is readily made at relatively low cost.

Referring now to FIG 3, a modification of the unit of FIGS. 1 and 2 is shown which involves a further simplification of the construction and arrangement for the firing and electric detonator. In this unit the left casing half 40, of substantially triangular shape, is shown with the longitudinally extending channel 29 and the transversely extending channel 33 intersecting at a right angle to each other as in the previous embodiment. In the channel 29 is the ventilated cylinder or chamber 19 containing the elongated timer element or plug 18 and with the piston or plunger 22 pressed against the plug 18 by the driving spring 28, as in the previous embodiment. Also the piston or plunger 22 is provided with the forwardly extending trigger pin through the center of the release spring 28 and the rearwardly extending guide rod 23. This is supported at the rear end by a bearing 42 in the casing and extends into a relief chamber 43 at the end thereof. Thus the chamber 19, in the present example, is closed at the rear end to provide a fixed timer system or unit. Also the cylinder or chamber 19 is ventilated by a single wide vent opening 41, instead of a plurality of smaller openings, as either is satisfactory provided sufficient area is available for the desired rate of evaporation of the solvent within a predetermined time limit.

Instead of a firing pin, the forward end of the release or trigger pin 26 extends through and holds an electrical contact 44 somewhat in the shape of the firing pin of the

previous example. This is provided with the driving spring 34 which seats against a spring base 45 in the channel. This, in turn, is supported by a fixed plug 46 pinned to the casing as in the previous example. Herein the spring base 45 is of conducting material for electrical circuit connections as will be seen and the plug 46 is of nonconducting or insulating material.

The electrical contact 44 is the moving firing element of the unit and upon release by the trigger pin 26 is adapted to engage the fixed firing element which is an opposite electrical contact 47 positioned in the channel 33 and supported by an insulating plug 48.

The contacts 44 and 47 are connected in circuit with an electrical detonator 49, self contained within the unit and connected with an energizing battery 50 also contained within the unit, as indicated. The movable contact 44 is electrically connected through the metal driving spring 34 with the conducting spring base 45, and the circuit connections with contacts are further completed through the detonator and the battery 50 by embedded circuit leads 51 in the unit and connected with the base 45 and the contact 47 as shown. The detonator and the battery may be of the hermetically sealed type. The whole unit is assembled as in the previous embodiment, by riveting the two halves or cover plates of the casing together at the points indicated in the figure by the rivet holes.

The operation of this embodiment is substantially the same as that of the previous one except that upon contracting of the elastomer timer plug 18 by evaporation of the solvent over a predetermined period of time, the piston or plunger 22, moving to the left under action of the driving spring 28 withdraws the release pin 26 from the contact 44 and this then moves to strike the contact 47, thereby completing an electrical circuit from the battery through the contacts and the spring 34 to the detonator which then fires and initiates any surrounding explosive material or nearby mines, for example if the detonator is amplified by the addition of explosives. It will be noted that the contact 44 may be pinned back in a safe position, while charging, by a safety pin 44A inserted therethrough, as in the previous example for the trigger pin.

Both embodiments of the invention can be adapted for use with a moving detonator rather than a moving firing pin as the moving firing element. Thus in FIG. 4 for example, as a modification of the unit shown in FIG. 3, the moving contact 44 is replaced by a moving plunger 53 which engages a primer or detonator body or plug 54. The latter is held in place until firing by the trigger pin 26 which projects beneath it into the channel 33. The safety pin 44A is then inserted just below the trigger pin 26 across the channel 33 and above the firing pin 55 which replaces the contact 47. The firing pin is thin and relatively flat and supported by a plug 56 in rear thereof in the channel 33.

Thus in the present embodiment, the unit may be assembled with all elements in place except the detonator 54, its follower 53, the spring 34, and the upper retaining cap. The unit is held together by the rivets and assembled as before, and immersed in the volatile solvent for an extended period of time during which the solvent expands the timer plug 18 and backs up the piston or plunger 22 driving it to compress the spring 28 and move the release pin 26 into the channel 33 and across it substantially in the position shown in FIG. 4. When the unit is removed from the solvent the safety pin 44 is then inserted to act as a safety pin during the assembly of the detonator. Subsequently the detonator 54 and its follower 53 are dropped into the channel 33, followed by the detonator spring 34 and the detonator spring plug corresponding to that at 46 in FIG. 3, and not shown in FIG 4. The plug is pinned in place and the safety pin 44A is then carefully removed and the unit is returned to the solvent and again completely immersed therein.

For its use, it merely requires exposure to the air to initiate the arming cycle. This can be interrupted by returning it to the liquid. In operation and exposed to the air, the volatile liquid evaporates and the timer material begins to contract. The release spring 28 pushes against the plunger 22 and the release pin or triggering pin 26 is moved toward withdrawal from under the detonator 54 as the material of the plug contracts because of the loss of volatile liquid. When the release pin 26 clears out of channel, the detonator 54 is immediately driven onto the firing pin 55 by the driving spring 34 and the plunger or follower 53 and may be used to explode any explosive material or elements surrounding the detonator and the unit.

From the foregoing description it will be seen that a time-delay or timing control unit in accordance with the invention may be of simplified low-cost construction involving a two-part separable casing of plastic material and with longitudinal and transverse cylindrical channels therein for the release and timing elements and for the firing elements, respectively. In the longitudinal channel a ventilated cylinder or chamber is provided which is filled with an elongated hollow timer element or plug or elastomer material with a spring-pressed movable piston or timer plug follower bearing against it and connected with a release or trigger pin for a movable firing element or pin in the other or transverse channel. The movable firing element or pin is associated with a fixed firing element which may be a detonator or an electrical contact. The timer element is expanded to fill the chamber and hold the firing pin locked when immersed in a volatile fluid to saturation. Thus a simple and effective low-cost time-delay detonator is provided for use in deactivation mines and demolition items in the field.

We claim:

1. A time-delay control unit for demolition operations and the like, comprising in combination:

a two-part separable casing of molded plastic material comprising two flat cover plates joined together and forming a longitudinally extending channel therethrough and a transversely extending channel therethrough at right angles to each other and intersecting, an elongated ventilated cylindrical chamber in said longitudinal channel between the ends thereof and terminating in a cylindrical threaded screw housing, an elongated round plug of elastomer material saturated with a volatile solvent filling said chamber from end to end, a spring-pressed plunger engaging one end of said plug within said chamber, a timer adjustment screw extending into housing to provide an axially adjustable backing for said plug at the opposite end from said plunger, fixed and movable control elements in said transverse channel, and a trigger pin engaging the movable control element and connected with said plunger to move therewith and release said movable control element for closure with said fixed element in response to contraction of said timer plug after a predetermined time provided by the evaporation of said solvent therefrom.

2. A time-delay detonator unit for mine destruction comprising in combination:

a two-part separable casing of molded plastic material comprising two flat cover plates joined together and forming a longitudinal extending channel therethrough and a transversely extending channel therethrough at right angles to each other and intersecting, an elongated ventilated cylindrical chamber in and along said longitudinal channel in spaced relation to the ends thereof, an elongated round timer plug of liquid saturable elastomer material expanded by a volatile solvent ab-

sorbed therein and filling said chamber from end to end, a spring-pressed follower engaging one end of said plug within the chamber, fixed and movable firing elements in said transverse channel, and trigger means engaging the movable firing element and connected with said plunger to move therewith and release said firing element to move into contact with said fixed firing element in response to contraction of said timer plug after a predetermined delay time provided by the evaporation of said solvent therefrom.

3. A time-delay detonator unit as defined in claim 2, wherein adjustable stop means including a cylindrical screw housing on said casing and an adjustment screw therein at the opposite end of said plug is provided to control the expansion limit of said plug and the delay time to functioning.

4. A time-delay detonator unit as defined in claim 2, wherein the fixed and moving firing elements are electrical contacts, and wherein firing circuit connections are provided therewith in said unit.

5. A timing control unit comprising in combination: a casing having a longitudinally extending channel therethrough, a ventilated cylindrical chamber in said channel, an elongated timer plug of elastomer material confined in said chamber and subject to expansion and contraction movement with the absorption and evaporation of a volatile solvent, a spring-pressed plunger engaging one end of said plug as a follower element therefor in expansion and contraction,

fixed and movable control elements in said casing at one end of said channel, and means engaging the movable control element and connected with said plunger to release said movable control element in response to contraction movement of said timer plug.

6. A timing control unit as defined in claim 5, wherein the casing is of a molded plastic material in the group comprising high-density polyethylene and polystyrene, and wherein the elastomer plug is a silicone rubber compound with a solvent in the group of alcohols of the low molecular type.

7. A timing control unit as defined in claim 6, wherein the silicone rubber compounds of the elastomer plug include one of a group including the Buna and styrene types, and wherein the alcohols of the low molecular type providing the solvent are in one of two groups including methanol, ethanol and propanol in one group and the chlorinated hydrocarbons such as carbon tetrachloride in the other group.

8. A timing control unit comprising in combination: a two-part separable casing of molded plastic material comprising two flat cover plates joined together and forming a longitudinally extending channel therethrough, an elongated ventilated cylindrical chamber in and along said channel between and spaced from the ends thereof,

an elongated round timer plug of elastomer material extending through said chamber and being saturable with a volatile solvent to expand and fill said chamber from end to end,

a spring-pressed plunger engaging one end of said plug within the chamber and movable therewith axially of the chamber in expansion and contraction as a follower element,

a fixed and a spring-pressed movable control element in said casing aligned in spaced relation for impact engagement upon release of said movable element from a cocked position,

a trigger pin engaging the movable control element and connected with said plunger to move therewith and release said movable control element in response to contraction of said timer plug after a predetermined time provided by the gradual evaporation of said solvent from said timer plug.

9. A timing control unit as defined in claim 7, wherein the plunger is provided with a trigger pin extending therefrom axially in one direction as the control element engaging means and with a central guide rod extending axially therefrom in the opposite direction longitudinally through said timer plug, and wherein an axially adjustable

timing screw is provided to hold said timer plug at the opposite end from the plunger to an expansion limit and the timing of said unit to functioning.
